UNITED STATES PATENT OFFICE.

ANDERS ANDERSSON ROSENGREN, OF MALMO, SWEDEN.

MACHINE FOR MAKING CAPS AND FOR APPLYING THE SAME TO BOTTLES.

1,377,279.

Specification of Letters Patent. Patented May 10, 1921.

Application filed June 30, 1920. Serial No. 293,039.

To all whom it may concern:

Be it known that I, ANDERS ANDERSSON ROSENGREN, a subject of the King of Sweden, and resident of 70^b Södra Förstadsgatan, 5 Malmo, in the Kingdom of Sweden, have invented certain new and useful Machines for Making Caps and for Applying the Same to Bottles, of which the following is a specification, reference being made to the 10 accompanying drawings.

The present invention relates to improvements in machines for capsuling or sealing bottles or other vessels.

In earlier machines for the manufacture 15 of capsules and for the capsuling or sealing of bottles or other vessels by means of capsules provided with a sealing disk, in which machines the blanks, of which the capsules are formed, are cut out or punched out by 20 one tool and the sealing disks by another tool, the tools are arranged co-axially, the one tool inclosing the other. This arrangement has been found to entail great inconveniences, especially when shavings of the 25 metal strip and fragments of the strip of cork or the like, from which strips the capsules and the sealing disks respectively are obtained, collect in the female dies in which the capsule blanks are formed into capsules, and have injurious effects both on the 30 forming of the capsules and on the working of the machine. The earlier machines of the above type cannot manufacture any but cylindrical capsules, and they are incapable 35 of making the so-called crown corks which are in extensive use.

The above-mentioned and other inconveniences are obviated and considerable advantages are attained by arranging machines 40 intended for the purposes in question in accordance with the present invention *i. e.* so that the said tools are situated or act successively to one another, that is to say so that a capsule is first formed in a female die 45 and then, after the female die has been moved, a sealing disk, which may be integral or composite, is placed in the capsule obtained.

The annexed drawings show by way of 50 example a form of the present invention adapted to a machine for the manufacture of crown corks and for the capping or sealing of bottles with them. Figure 1 shows a vertical section and Fig. 2 a horizontal 55 section of the machine head, which contains the parts operating in the manufacture of

the capsules and the sealing of the bottles, while Fig. 3 shows a detail in section. Fig. 4 is a diametrical section of one of the caps. 60

As in earlier machines for the said purpose (for example the applicant's Swedish Patent No. 40480) there is rotatably located in the machine head a cylinder 1, wherein there are female dies, in which the capsules 65 are formed, and which cylinder rotates intermittently in the manner described below. The power required for this movement and for the movement of other parts situated in the machine head is supplied from an intermittently rotated vertical shaft 2 driven from the main shaft of the machine, and the device for bringing about the intermittent movement of the female die cylinder 70 may be constructed in any suitable manner 75 whatever.

The shaft 2 is provided with a fixed miter gear 2^a, which drives a similar gear 2^b on the shaft 22. The gear 2^b is provided with a hub 2^c to which is fixed a gear 2^d, which 80 drives a gear 2^e fixed to the cylinder 1. In this manner the cylinder 1 is driven from the shaft 2.

The female die cylinder 1 is provided with two diametrically situated female dies. 85 Each of said female dies is formed of a bottom piece 3, which is firmly fastened to the cylinder by a bolt 4, and of a sleeve 5 surrounding the bottom piece and slidable around it. The displacement of the sleeves 90 5 is effected in the manner and for the purpose stated more clearly hereinafter.

Above the female die, being in position for the forming of a capsule, is situated the tool for the production of the capsule 95 blanks. Said tool consists of a tubular punch 6, which is movable in a vertical direction, and which, with the aid of a punch die 6^a, punches the capsule blanks out of a strip (not shown) consisting, for instance, 100 of aluminum, iron or an alloy, said strip being intermittently fed forward under the tubular punch 6 (*i. e.* through the channel 7) by a pair of cam rollers 8. These rollers are provided with meshing gears 8^a—8^b, the 105 latter of which is fixed to a shaft 8^c. A gear 8^d is fixed to the shaft and meshes with a gear 8^e fixed to the shaft 22. It will thus be seen that the rollers 8 are driven from the shaft 22. 110

In the tubular punch 6 there is a piston 9, likewise movable in a vertical direction and

at the lower end of which there is a male die 10, the shape of which corresponds to the desired shape of the capsules.

The device by which the required movement is imparted to the tubular punch 6 and the piston 9 or the male die 10 respectively may be of any kind desired. Power for this operation is obtained from the main shaft by means of a reciprocating link 11^a, which 10 rocks a lever 11 that is connected to the piston 9.

Fingers 9^a are pivotally mounted in the head of the machine and engage notches 9^b in the sides of the piston 9. When the piston 15 ton 9 is depressed, the fingers are swung downwardly until they engage the upper end of the punch 6, and further downward movement of the piston 9 causes the fingers to depress said punch.

20 After a capsule blank has been punched out of the blank strip by the tubular punch 6 during the downward movement of the latter, it is carried by the tubular punch down toward the upper edge of the female 25 die and lodges centrally on the female die between which and the tubular punch it is held firmly until the male die 10, by a drawing operation on the blank, descends into the female die and forms a capsule. In the 30 present case the capsule is assumed to be a capsule for a so-called crown-cork.

After the above described process and when the tubular punch 6 and the male die 10 have been carried by a spring 6^b back to 35 their original positions, the female die cylinder 1 revolves a quarter turn counterclockwise (Fig. 1), so that the female die with the newly formed capsule situated therein will be opposite to the tool for the 40 forming of the sealing disks. This tool is shown to consist of a punch piston 12, which coöperates with a punch die 12^a and which receives its functional movement from a cam disk 13 driven through the gearing 13^a, 13^b, 13^c, 13^d and 13^e from the shaft 2, its 45 return movement being effected by a spiral spring 14. The strip, consisting of cork or other suitable material (and which also may be composed of several different strips and 50 materials), from which the sealing disks are punched out, moves beneath a plate 15 to cam rollers 16, by which the ribbon is intermittently fed down to a position in front of the punch piston 12. After a sealing disk 55 has been punched out, it is driven by the punch piston through the punch die and into the newly formed capsule situated opposite those parts, against the bottom of which the sealing disk is pressed, as will be 60 seen from Fig. 4, which shows a section of a crown cork with sealing disk. The rollers 16 are provided with meshing gears 16^a, one of which is fixed to a shaft 16^b, having a fixed gear 16^c driven from a gear 16^d fixed to 65 the hub of the gear 13^a.

When the newly formed capsule has been provided with a sealing disk, the female die cylinder revolves another quarter turn in the previously indicated direction, in consequence of which the female die hitherto referred to will be in a position for sealing a bottle 17 by means of the capsule situated in said die. The other female die in the female die cylinder will simultaneously be in a position for forming another capsule. 75

Against the bottoms of the sleeves 5, which together with the bottom pieces 3 form the female dies, rest levers 18, each of which at one end is pivotally fixed in the female die cylinder and the other end of 80 which is acted upon by a member 19 forming one arm of a double-armed lever, the other arm 20 of which is acted upon by a cam 21 on a shaft 22 driven from the shaft 2.

When a female die containing a capsule provided with a sealing disk has reached the position just stated, *i. e.* the sealing position, the cam 21 acts on the lever 20, the arm 19 of which in turn acts on the lower one of the levers 18, in consequence of which 90 the corresponding female die sleeve 5 is pressed downward. A moment previously, the bottle 17 which is to be sealed has been moved upward, so that the mouth of the bottle is held strongly jammed against the 95 sealing disk in the capsule, while the female die sleeve is moving downward. During its downward movement the sleeve acts on the edge portion 23 (see Fig. 4) of the capsule, whereby the knee-shaped portions 24, 100 which are situated between the edge portion 23 and the cylindrical or somewhat conical capsule portion 25, which surrounds the sealing disk, are caused to engage with a groove which in the usual manner is arranged on the bottle neck under the bottle mouth. The sealing of the bottle is now completed. During the process just described a fresh capsule has been formed in the upwardly facing female die. When the 110 sealed bottle has been lowered somewhat, the female die cylinder turns again, so that the new capsule will come into position to be provided with a sealing disk, and then the cylinder is turned again for the purpose 115 of bringing the capsule provided with a sealing disk into the position to be applied on a following bottle. This cycle may be continued as long as desired.

The return movement of the female die sleeves 5 is effected by spiral springs 5^a.

On the outer end of the channel 7 there is a shear device 26 driven from the lever 11 for cutting the part of the capsule blank strip, from which the blanks have been 125 punched out, into short pieces, which fall down into a suitable receptacle.

Sealing machines arranged in accordance with this invention may be constructed otherwise than has been stated by way of 130

- example. Thus, for example, the female die cylinder (or corresponding part), instead of being provided with a pair of female dies, may be provided with two or more pairs. 5 In this case, obviously, each rotary movement of the female die cylinder will be of less extent than when only one pair of female dies is provided. A specially important form of the invention is the one, in 10 which two, three or more capsules are simultaneously made, simultaneously provided with sealing disks, and simultaneously placed on a corresponding number of bottles. The female die cylinder in such a machine should in this case be placed at an angle of ninety degrees to the position shown in Fig. 1 (*i. e.* its shaft should be swung at ninety degrees in a horizontal plane), and the duplicated or manifolded 15 members for the production of the capsules, for providing the latter with sealing disks and for applying them on the bottles should be arranged in conformity therewith.
- It is obvious that other capsules than so-called crown corks can be made with machines constructed in accordance with this invention. Thus, for example, capsules with a smooth or folded circumference can be made with them. 20
- With regard to the arrangement of the details shown, it should be observed that the springs, which effect the return movement of the respective members, may suitably be replaced by devices which ultimately will be found more reliable than springs; springs have been shown in the drawings only for convenience of illustration. 25
- Having now described my invention, what I claim as new and desire to secure by Letters Patent is:
1. In a machine for making caps and applying the same to vessels, a female die member, means for cutting out a cap blank and for forcing said blank into the die member to form a capsule, means for forcing the cap from the die member and for applying the same to a vessel, means for moving the die member from the position where it receives the blank to the position where it discharges the same, and means located adjacent to the path of movement of said die member for forming a sealing disk and for applying the same to the previously formed blank. 50
  2. In combination means for forming a metal capsule, a die forming part of said means, sealing disk forming means, means for shifting the die from the capsule forming means to said sealing disk forming means, means included in the disk forming means for moving a disk into a capsule carried by the die, and means coöperating with said die for crimping the cap carrying the disk onto a vessel. 55
  3. The combination with a metal cap forming mechanism and a sealing disk forming mechanism, of a die forming part of the metal cap forming mechanism and designed to receive a cap from said cap mechanism and movable to a position to receive a sealing disk formed by said disk mechanism, and means coöperating with said die for applying a formed cap to a vessel. 65
  4. In a cap making and applying machine, a capsule former and crimping means including a movable female die, means for bringing a strip of sheet material into a position across the axis of said die, a metal die coöperating with the first die for forming the sheet material into capsule shape, means for shifting the first named die out of axial alignment with the second die, and a hollow crimping member surrounding the first die, carried by the last named means and designed to crimp the capsule upon the neck of the bottle. 70
  5. A combination as defined in claim 4 having means for shifting said hollow member to cause the same to crimp the capsule on the bottle neck. 75
  6. A combination as defined in claim 4 in which the hollow member is provided with means for shifting the same, said means including an oscillating lever, and cam actuated means for operating said lever. 80
  7. A combination as defined in claim 4 in which the hollow member is provided with means for shifting the same, said means including a pivotally mounted lever, a double arm pivotally mounted lever designed to actuate the first named lever, and a cam engaging said double arm lever. 85
  8. A combination of the kind defined by claim 4 in which the hollow member is provided with resilient means for normally holding the same in inoperative position. 90
  9. A combination as defined in claim 4 in which springs bear against said hollow member for holding the same in inoperative position, and means for shifting said hollow member out of its inoperative position to cause the same to crimp a capsule on a bottle neck. 95
  10. A machine for making caps and for applying the same to vessels comprising a rotatable carriage, a first die member fixed to said carriage, means for cutting a blank sheet material into substantially disk shape, a second die coöperating with the first die in one position of said rotatable member for forming the previously cut blank into a capsule having a skirted edge, a sealing disk forming means having its axis arranged at an angle to the axis of the second die and designed to insert a sealing disk in the previously formed capsule when said rotatable member has been shifted from its original position, and means for crimping the com- 115
  - 120
  - 125

- pleted cap upon a bottle neck after said rotatable member has been shifted or moved from its second position.
11. A combination as defined in claim 10 in which the means for cutting the sheet material blank includes a hollow die.
12. A machine of the kind defined by claim 10 in which the means for cutting the sheet material blank comprises a hollow die, and resilient means for normally holding the same in inoperative position.
13. A machine of the kind defined by claim 10 in which the means for forming the sealing disk includes spaced guides, one of which is provided with an aperture, and a plunger coöperating with said aperture for cutting a disk from a strip of material fed between said guides, and means for feeding strip material to said guides.
14. In a machine for making caps and for applying the same to bottle necks, a rotatable member carrying a plurality of relatively fixed dies, hollow crimping plungers surrounding said dies and designed to crimp bottle caps carried by said dies, and lever mechanism operated in said rotatable member and engaging said hollow members for moving said hollow members relatively to the dies for crimping caps carried by the dies, and means for actuating said lever mechanism.
15. A machine for making caps and for

applying the same to vessels comprising a rotatable cylindrical carriage, a plurality of radially arranged female dies carried by said carriage and having their axes arranged perpendicularly to the axis of said carriage, hollow plungers surrounding said dies and coöperating with said dies to crimp capsules on bottle necks, lever mechanism mounted in said carriage and engaging said hollow plungers, means for actuating said lever mechanism to cause movement of the hollow plungers relatively to the dies, mechanism for cutting out and for forming a sheet material blank into one of said dies when the axis of the last named means is coaxial with the axis of one of said dies, a plunger for cutting out a sealing disk arranged at an angle to the axis of the sheet material cutting mechanism and coöperating with one of said dies for forcing a blank of sealing material into the capsule carried by one of said dies, and means for actuating said lever mechanism whereby one of the first mentioned hollow plungers will crimp the completed cap upon a bottle neck.

In witness whereof I have hereunto set my hand in presence of two witnesses.

ANDERS ANDERSSON ROSENGREN.
